UNITED STATES PATENT OFFICE.

OSCAR KITCHELL, OF VALPARAISO, INDIANA.

EGG-BEATER.

SPECIFICATION forming part of Letters Patent No. 308,901, dated December 9, 1884.

Application filed April 17, 1884. (No model.)

To all whom it may concern:

Be it known that I, OSCAR KITCHELL, a citizen of the United States, residing at Valparaiso, in the county of Porter and State of Indiana, have invented certain new and useful Improvements in Egg-Beaters, of which the following is a specification, reference being had therein to the accompanying drawing.

This invention has relation to improvements in that class of devices known as egg-beaters; and it consists in the construction and novel arrangement of the same, all as will be hereinafter more fully explained, and particularly pointed out in the claim appended.

15 The annexed drawing, to which reference is made, fully illustrates my invention, in which the figure represents a perspective sectional view of a vessel, showing my improved beater applied thereto.

20 Referring by letter to the accompanying drawing, A designates a vessel of any suitable construction, which is provided with a lid, B, that is centrally perforated, through which projects the upper end of a vertical rod, C, 25 having secured thereto a pinion, D, which meshes with a gear-wheel, E, journaled in a bearing-plate, F, secured to the top of the cover. This vertical rod C is provided at its 30 lower end with a cone-shaped bearing, G, in which is the bearing-pin or lug H, that is secured to the bottom and on the inside of the vessel aforesaid.

I indicates the beater, consisting of the four blades J, which curve from their upper end, K, downwardly and inwardly, as at L, and at the lower end thereof the same is bent upwardly and inwardly, as shown at M, and se-

cured to the rod C. These blades, as at N and O, are constructed of a single piece of metal, as well as the pair P and R, and about the center of each pair of blades are secured oblique blades or braces S, which assist in beating or mixing the contents of the vessel, and at the same time serve as braces for the blades J.

40 It will be observed from the above description, and by reference to the drawing, that the operation of my device is very simple. The operator turns the crank on the gear-wheel, thus, through the medium of the same, imparting motion to the beater through the pinion, when said beater revolves rapidly, turning on the pivot-bearing in the bottom of the vessel, and thereby thoroughly mixing the contents of the vessel.

45 Having described my invention, what I claim, and desire to secure by Letters Patent, is—

50 The herein-described egg-beater, consisting of the blades J, constructed in pairs, curving outwardly and downwardly, and then upwardly, and connected to the rod C, and provided with the oblique braces S, the rod C, having the cone-shaped bearing G, pivot-bearing H, 55 pinion D, gear-wheel E, having the crank-handle, vessel A, cover B, and plate secured thereto, the whole arranged as shown, described, and for the purpose specified.

60 In testimony whereof I affix my signature in presence of two witnesses.

OSCAR KITCHELL.
